UNITED STATES PATENT OFFICE.

JOSEPH B. SINGER AND ARTHUR B. LEVY, OF NEW YORK, N. Y.

FOLDING DISPLAY-BOX.

1,361,631.

Specification of Letters Patent. Patented Dec. 7, 1920.

Application filed May 28, 1920. Serial No. 384,817.

To all whom it may concern:

Be it known that we, JOSEPH B. SINGER, a citizen of the United States, and resident of the city of New York, county and State of New York, and ARTHUR B. LEVY, a citizen of the United States, and resident of the city of New York, county and State of New York, have invented certain new and useful Improvements in Folding Display-Boxes, of which the following is a description.

The present invention relates to improvements in folding display boxes, and has for its primary object to provide a box comprising a container portion, a cover, and a hinged connecting member therebetween, the whole being formed of one piece of material and adapted to be maintained in set-up position without the use of glue, staples or other such means, and in a manner as to provide a thoroughly protective box, and at the same time a very attractive one when placed in display position.

We further propose to provide a display panel portion forming a part of the one-piece construction and a bottom construction for the container portion of the box of double thickness, and from the outer thickness of which the hinged member is formed.

Another object is to produce a blank so arranged as to conserve material, it being possible to arrange for cutting several blanks from a sheet, so that projections on one blank extend into recesses of the adjacent ones.

A further important object is to provide a novel interlocking means adapted to greatly facilitate the setting up of the boxes, and to relieve, to a great extent, injury or wear upon the fingers of the operator setting up such box, the construction doing away with the necessity of handling the interlocking tongue portions, and the pressing out or holding of the cut-out portions for receiving the tongue, as has been the necessary procedure heretofore in other types of boxes.

With these and other objects in view, an embodiment of our invention is shown in the accompanying drawings, and this embodiment will be hereinafter more fully described with reference thereto, and the invention will be finally pointed out in the claims.

In the accompanying drawings:

Figure 1 is a perspective view of a box

formed according to our invention, and showing the same in set-up display position.

Fig. 2 is a perspective view of the same closed, and showing the under side thereof.

Fig. 3 is a plan view of the blank from which the box is formed.

Fig. 4 is a vertical longitudinal sectional view through the box, and showing the container portion and the cover portion spaced from each other by means of the hinged connecting portion.

Fig. 5 is a transverse sectional view taken along the line 5—5 of Fig. 4.

Fig. 6 is a fragmentary perspective view showing the interlocking parts at one end of the container portion before the same are brought into actual interlocking relation, and,

Fig. 7 is a similar view showing the parts in interlocking relation, and forming one end of the container portion of the box.

Similar reference characters indicate corresponding parts throughout the several views of the drawings.

Referring to the drawings, and more particularly to Figs. 1 and 2 thereof, the box, according to our present invention, comprises generally a container portion A adapted to contain the goods, a cover portion B, adapted to telescopically engage the container portion in the closed position of the box, and to support the same raised at one end, and in inclined display position when open, and a connecting hinged member C hingedly connected at one end to the edge of one end of the cover, and at its other end to the base of the container portion substantially along its center and along a transverse hinged line, the hinged member adapted, during the opening of the box, to guide the cover into engagement with the under side of the container portion to support the same in inclined display position. This general type of box is disclosed in our pending application, Serial No. 125,575. A display panel D is provided at the upper edge of the rear end of the container portion lying flat upon the goods contained in the box in the closed position, and adapted to be raised in open position, as shown in Fig. 1.

Referring now to Fig. 3, the blank from which the box is formed, comprises an elongated central portion consisting of an end flap 10, provided with tongues 11 and 12, projecting from its ends, two end portions 110

- 13 and 14, a rectangular bottom portion 15, an end portion 16, a top display panel portion 17 partially scored, transversely and centrally adjacent the side edges, as at 18 and 19, a display portion 20 of any desired shape, and preferably ornamental, projecting from the half of the portion 17, adjacent the portion 16 into a cut-out 18', in the other half. Adjacent the portion 17 there is provided an end flap portion 21, a rectangular bottom portion 22, provided with an interior transverse score line 23, spaced from the longitudinal side edges and connecting at its ends to the ends of slits 24 and 25 extending to the corners at one end of the portion 22, thereby forming a hinged part 26, adapted to be swung about the line 23. To the end of the connected part 26 there are connected the parts of the blank from which the cover of the box is adapted to be formed, and comprising, in part, an end portion 27, a top portion 28, a pair of end portions 29 and 30 and an end flap 31, having projecting tongues 32 and 33 at its ends.
- At the ends of the end portion 21 there are provided flaps 34 and 35, and along the longitudinal edges of the bottom portion 22 there are provided pairs of side portions 36, 37 and 38, 39, the portions 37 and 39 adapted, as will presently more fully appear, to be folded inwardly upon the portions 36 and 38.
- At the ends of the portions 37 and 39, removed from contiguity to the end portion 21 and the flaps 34 and 35, there are provided flaps 40 and 41, and adjacent the same, and in the longitudinal free edges of the said portions 37 and 39 there are provided cut-outs 42 and 43, of semi-circular shape, and of such size as to permit insertion therein of the semi-circular tabs or tongues 11 and 12 of the flap 10 for the purpose of locking the box in set-up position, as will hereinafter be more fully pointed out.
- Extending from the longitudinal edges of the portions 27 and 28 there are provided side forming parts, similar in form to the parts 34 to 43, and comprising flaps 44 and 45, pairs of side portions 46, 47, and 48, 49, flaps 50 and 51 being provided at the ends of the portions 47, 49, and semi-circular cut-outs 52 and 53 being provided in the longitudinal free edges of the portions 47 and 49, and adapted, as will presently appear, to have the semi-circular tabs or tongues 32 and 33 interlockingly engaged therein.
- The operation of setting up the box is as follows:
- The blank is first folded upon the lines 18 and 19, so that the portion 17 is folded upon itself, the part 20 projecting therefrom, while the end portion 16 and the bottom portion 15 overlie the end portion 21 and the bottom portion 22. The end portions 16 and 21, together with the portion 17, are bent upwardly at right angles to the bottom portions 15 and 22, and the flap extensions 34 and 35 of the portion 21 are bent forwardly into line with the longitudinal side edges of the bottom portions, whereupon the portions 36 and 38 are folded upwardly at the outer side of the portions 34 and 35, and the portions 37 and 39 downwardly at the under side, embracing the same. The end flaps 40 and 41 are folded inwardly in line with the transverse ends of the bottom portions, and are embraced by the end portions 13 and 14, the portion 14 being bent upwardly from the bottom portion 15 at the outer side of the flap, while the portion 13 is bent downwardly at the inner side. During this last action the flap 10 is carried down into engagement with the bottom, as indicated in Fig. 6, and the tabs 11 and 12 at the ends, automatically enter the cut-outs 42 and 43, the box being thereby locked in set-up position, as shown in Fig. 7. It will be seen that during this action the tabs will be bent substantially at right angles to the flap 10, as they engage the inner side portions of the box, and as they come into relation with the cut-outs 42 and 43 their inherent springiness will cause them to expand into locking relation therewith, the slightly inward movement of the portion 13, due to its inherent springiness, moving the tabs into offset relation with the cut-outs and beneath the portions 37 and 39, so that the box is thereby effectively locked in set-up position, and without the necessity of the operator touching the tongues or flaps, or the cut-outs.
- The container portion of the box is thus formed, and the cover portion remains to be formed, the parts of the blank, therefore, being hingedly connected to the bottom of the container portion by the hinged portion 26. The end portion 27 is bent upwardly at right angles to the bottom 28, the flaps 44 and 45 forwardly along the longitudinal edges of the bottom portions, and are embraced by the folding upon themselves of the side portions 46 and 47, and 48 and 49. The flaps 50 and 51 are bent inwardly, and are embraced by folding upon themselves of the end portions 29 and 30, the tabs 32 and 33 interlockingly engaging the cut-outs 52 and 53 in a similar manner to the interlocking of the flaps 11 and 12 with the cut-outs 42 and 43 of the container portion. The box is now complete.
- Among the advantages of our improved box may be pointed out the extreme facility of setting up the boxes, the economy of manufacture due to the forming of the box from a single blank, and without the use of glue, staples or other extraneous means, the thoroughly protective nature of the box, all of the walls and the bottom of the container

portion being of double thickness, and the attractive and easy to set up counter display that the box affords.

As above pointed out, the particular interlocking means may be placed in interlocking position without the necessity of the operator handling the tongues and cut-out portions. It has been found heretofore that very serious injury often resulted to the fingers of the operator, due to the excessive handling of the sharp edges of the cut-out portions, and the tongues. This is obviated in the present device, and the same may be set up with a great many less movements on the part of the operator, and, therefore, a greater number of boxes may be set up within a given time.

The arrangement of the parts of the box is such that when set up, the visible portions thereof are all on one side of the blank, so that cardboard, having only a finished surface on one side, need be used and the whole exposed surface of the box may be printed with suitable decorative and advertising matter descriptive of the goods contained in the box by printing on one side of the blank only.

We have illustrated and described a preferred and satisfactory embodiment of our invention, but it is obvious that changes may be made therein within the spirit and scope thereof, as defined in the appended claims.

We claim:

1. A one-piece folding display box formed from a blank comprising container and top forming portions, the container forming portion consisting of two spaced bottom portions adapted to be folded into superimposed relation, one being outer and one inner, end forming portions at the overlying edges of one end of each of said bottom portions adapted to form a double thickness end wall, side wall forming portions at the longitudinal edges of one of said bottom portions, means adapted to interlockingly connect said side wall forming portions to said end wall forming portions at one end, and end wall forming portions connected to one end of one of said bottom portions, means adapted to interlockingly connect said side wall forming portions at their other ends to said last-named end forming portions, a hinged connecting portion extending from the outer bottom portion, the cover portion comprising a top portion, end forming portions, one of which is connected to said hinged connecting portion, and side forming portions adapted to be connected at their ends to said end forming portions, said top adapted to telescopically engage the container portion, said hinged connecting portion adapted to guide the same into closed and open positions.

2. A one-piece folding display box formed from a blank comprising container and top

forming portions, the container forming portion consisting of two spaced bottom portions adapted to be folded into superimposed relation, one being outer and one inner, end forming portions at the overlying edges of one end of each of said bottom portions adapted to form a double thickness end wall, a display panel portion disposed between said end forming portions foldable along its center transverse line to project above said end portions, side wall forming portions at the longitudinal edges of one of said bottom portions, means adapted to interlockingly connect said side wall forming portions to said end wall forming portions at one end and end wall forming portions connected to one end of one of said bottom portions, means adapted to interlockingly connect said side wall forming portions at their other ends to said last-named end forming portions, a hinged connecting portion extending from the outer bottom portion, the cover portion comprising a top portion, end forming portions, one of which is connected to said hinged connecting portion, and side forming portions adapted to be connected at their ends to said end forming portions; said top adapted to telescopically engage said container portion, said hinged connecting portion adapted to guide the same into closed and open positions.

3. A one-piece folding display box formed from a blank comprising container and top forming portions, the container forming portion consisting of two spaced bottom portions adapted to be folded into superimposed relation, one being outer and one inner, end forming portions adapted to form a double thickness end wall, a display panel portion disposed between said end forming portions foldable along its center transverse line to project above said end portions, an extension of half of said panel portion extending into an opening of the other half, and adapted to project above the same in display position, side wall forming portions at the longitudinal edges of one of said bottom portions, means adapted to interlockingly connect said side wall forming portions to said end wall forming portions at one end and end wall forming portions connected to one end of said bottom portions, means adapted to interlockingly connect said side wall forming portions at their other ends to said last-named end forming portions, a hinged connecting portion extending from the outer bottom portion, the cover portion comprising a top portion, end forming portions, one of which is connected to said hinged connecting portion, and side forming portions adapted to be connected at their ends to said end forming portions, said top adapted to telescopically engage said container portion,

- 4 said hinged connecting portion adapted to guide the same into closed and open positions.
- 5 4. A one-piece folding display box formed from a blank comprising a container, and top forming portions, the container forming portion consisting of two spaced bottom portions, adapted to be folded into superimposed relation, one being outer and 10 one inner, end forming portions at the overlying edges of each of said bottom portions adapted to form a double thickness end wall, side wall forming portions at the longitudinal edges of one of said bottom portions, 15 means adapted to interlockingly connect said side wall forming portions to said end wall forming portions at one end, and end wall forming portions connected to one end of one of said bottom portions, means adapted 20 to interlockingly connect said side wall forming portions at their other ends to said last-named end forming portions, a hinged connecting portion cut from said outer bottom portion, and extending substantially 25 from the center of said bottom portion along a transverse hinged line to one end of said bottom portion, the cover portion comprising a top portion, end forming portions, one of which is connected to said hinged connecting portions, and side forming portions 30 adapted to be connected at their ends to said end forming portion, said top adapted to telescopically engage said container portion, said hinged connecting portion adapted 35 to guide the same into closed and open positions.
5. In a folding display box, a bottom portion, side and end wall forming portions at the respective edges of said bottom portion, 40 the portions along two parallel edges of said bottom portion being each foldable centrally along a longitudinal line to form a double thickness wall, the portion at one of the other edges being foldable along a central longitudinal line to form a double thickness wall, said parallel double thickness walls being each provided at their inner side and along their lower edges contiguous to the said other double thickness wall, with 50 a cut-out portion, and means on the inner portion of said other double thickness wall adapted to enter said cut-outs between the superimposed portions of said parallel walls to lockingly hold said parallel double thickness walls and said other double thickness 55 wall in set-up relation, and means on the remaining of said walls adapted to be interlockingly engaged with said double thickness walls.
6. In a folding display box, a container portion consisting of a double thickness bottom, side and end walls extending along the edges of said bottom, a hinged member integral with the outer portion of said double thickness bottom, and a top portion permanently connected to said hinged member. 60
7. A folding display box comprising a container portion consisting of a double thickness bottom portion, side and end walls extending along the edges of said bottom portion, a hinged connecting portion cut from the outer portion of said double thickness bottom and integrally and hingedly connected thereto along a transverse hinged line substantially centrally of said bottom portion, a cover portion comprising a top and side and end walls, said hinged connecting member being connected to the upper edge of one of the walls of said cover portion. 65
8. A one-piece folding display box comprising a container portion consisting of a double thickness bottom portion, side and end walls extending along the edges of said bottom portion, a hinged connecting portion cut from the outer portion of said double thickness bottom and integrally and hingedly connected thereto along a transverse hinged line substantially centrally of said bottom portion, a cover portion comprising a top and side and end walls, said hinged connecting member being integrally connected to the upper edge of one of the walls of said cover portion. 70
